UNITED STATES PATENT OFFICE

WILLIAM ISLER, OF CANTON, OHIO, ASSIGNOR TO THE BERGER MANUFACTURING COMPANY, OF CANTON, OHIO, A CORPORATION OF OHIO

LATCH FOR LOCKERS

Application filed March 6, 1928. Serial No. 259,497.

This invention has for its object the provision of a latching mechanism for a locker or other enclosure, which will be simple in operation, sturdy in construction, permit of easy assembly, and present withal a neat and attractive appearance.

Another object of the invention is to provide a locker door having a tubular formation at the edge thereof, which formation functions not only to reinforce the locker door, but at the same time serves as a bearing or supporting surface for slidably supporting a latching bar, and also serves to conceal the connection between the latching bar and the door handle which is adapted to be directly connected thereto.

In copending application of Joseph Sturm and William L. Caldwell, Serial No. 115,538, there is described a latching mechanism for a locker in which a latching bar is enclosed in a tubular housing or reinforcement at the edge of the door, the bar being positively forced into latching position by means of an especially designed hook or keeper which enters the housing and engages slots in the latching bar. In assembling the aforesaid latching mechanism, it is necessary to insert the latching bar into one end of the housing and to push the bar up into the housing to a position in which it may be engaged by the tenons of an especially designed handle.

In accordance with the present invention, the positioning or assembling of the latching bar and handle is considerably facilitated by virtue of the fact that the latching bar is placed on the exterior of the tubular housing or reinforcement in a natural and simple manner, the bar being designed to be positively moved into latching position in the same manner as the latching bar described in the aforesaid application of Sturm and Caldwell.

These and other objects of the invention will become more readily apparent in the course of the following description of one embodiment of the invention, taken in connection with the accompanying drawings wherein

Fig. 1 is a front elevation of a locker in which is embodied the novel features of the present invention;

Fig. 2 is a cross-section through the tubular housing and the latching bar, taken on the line 2—2 of Fig. 3;

Fig. 3 is a cross-section through the door and adjacent portions of the locker, taken on the line 3—3 of Fig. 1;

Fig. 4 is an exploded view of a portion of the tubular housing, latching bar, and keeper;

Fig. 5 is an exploded view of the handle, a portion of the tubular housing, and latching bar, showing the manner in which the handle is adapted to be connected to the latching bar;

Fig. 6 is an elevation of the upper end of the tubular housing, showing the manner in which the latching bar is positioned on the housing;

Fig. 7 is a cross-section taken on the line 7—7 of Fig. 6;

Fig. 8 is a cross-section taken on the line 8—8 of Fig. 6;

Fig. 9 is a cross-section taken on the line 9—9 of Fig. 2; showing the manner in which the handle is secured to the latching bar;

Fig. 10 is an exploded view of a portion of the tubular housing, the latching bar, and the rivet for securing the bar on the housing;

Fig. 11 is a cross-section through a modified form of the housing and latching bar.

Referring more particularly to the drawings, the locker comprises a sheet-metal body 1, and a door 2 hinged thereon. The door 2 is formed at one of its side edges with a tubular reinforcement or housing 3, closed at the top by a flange 4, and open at the bottom to facilitate removal of the mandrel used in forming the housing.

Disposed at vertically spaced intervals, preferably near the top, bottom, and middle of the housing 3, are slots 5 which serve to receive keepers 6 mounted on the locker body 1, when the door 2 is closed. The keepers 6 are formed with an upwardly sloping edge 7, a downwardly sloping edge 8 approximately twice as long as the upwardly sloping edge, and a seat 9. Keyhole slots 10 enlarged at one end as at 11 are formed in the rear face of the housing 3, one of these slots being positioned above the uppermost slot 5, and the other a

short distance below the lowermost slot 5. The front face of the tubular housing has formed therein, slots 12 which serve to receive tenons 13 of a handle 14.

5 The latching bar 15, preferably made in the form of a channel for strength, has secured thereto near each end, a rivet 16 having a shoulder 17 and an enlarged head 18. Secured at or near the middle portion of the 10 web of the bar, as by spot welding, are clips 19 having legs 20 and 21, provided with apertures 22, the apertures in legs 21 being threaded. The latching bar has formed therein at vertically spaced intervals, slots 23 terminating in upper edges 24 and lower edges 25, which are spaced to coincide with the slots 5, and which serve a purpose to be presently described.

15 The latching bar 15 and handle 14 are 20 assembled on the housing in the following manner:

The web of the latching bar is placed adjacent the rear face of the housing 3 in such a manner that the enlarged heads 18 of the 25 rivets 16 pass through the enlarged ends 11 of the keyhole slots 10. The bar is then moved upwardly until the legs 20 and 21 of the clips 19 are opposite the slots 12 in the front face of the housing. The upward 30 movement of the bar causes the shoulders 17 of the rivets 16 to ride up into the keyhole slots 10, and the enlarged heads 18 of the rivets prevent the bar from being subsequently pulled away from the housing. The handle 35 14 is then placed on the door in such a manner that the tenons 13 enter the slots 12 in the front face of the housing 3 and lie alongside the legs 20 and 21 of the clips 19, as clearly shown in Figs. 2 and 9. Adjacent the 40 slots 12, a portion of the rear and inwardly directed lateral wall of the housing 3, and a corresponding portion of one of the flanges of the latching bar 15 are notched out to facilitate the positioning of the latch bar, 45 and to permit the insertion of screws 26 having threaded ends 27 for the purpose of securing the handle to the latching bar.

50 It will be apparent from a consideration of Figs. 2 and 4, that when the door is closed, the upper edges 24 of the slots 23 in the latching bar will ride up over the upwardly sloping edges 7 of the keepers 6, until the uppermost point of these edges is reached. The lower edges 25 of the slots will then begin to 55 contact with the downwardly sloping edges 8 of the keepers, and the edges 24 of the slots will be positively forced to move down into the seats 9. In this manner, the locker door is effectively shut or latched, regardless of 60 how great a force is used to effect closing.

65 In Fig. 11, a modified form of the housing and latching bar are shown. The housing 3 has vertically extending grooves 28 in the lateral walls thereof, and the latching bar 15 has inwardly directed flanges 29 which fit

into these grooves. This form of the invention does away with the necessity of providing a bayonet connection of the latching bar to the housing, as shown in Figs. 6, 7, and 8.

70

Claim:

The combination with a locker door having a tubular reinforcement at one edge thereof, of a handle, a latching bar of channel cross-section movably secured to and embracing said reinforcement; said latching bar having clips thereon extending into the tubular reinforcement, and said handle having tenons thereon extending into the reinforcement and secured to said clips.

75

In testimony whereof I affix my signature.

WILLIAM ISLER.
